FOOT SUPPORT

Albert Augusta, Cleveland, Ohio

Application July 30, 1932. Serial No. 626,685

8 Claims. (Cl. 36—8.5)

This invention relates to a foot support for use by those suffering from diseases or injuries of the metatarsophalangeal joint, or of the bones or joints of the phalanges anterior thereto.

5 While a special shoe might be constructed, embodying the principle of my invention, I prefer to provide a support to be secured to the sole of an ordinary shoe. The support conforms to the normal contour of a foot or shoe sole and 10 extends from the rear of the foot forward to a position beneath the heads of the metatarsal bones. My support holds the foot in substantially normal position, but in a plane substantially higher than and parallel to the normal 15 position. By the use of my support the metatarsophalangeal joint is supported at such a height that the user may walk comfortably without flexure of that joint or of the bones or joints anterior thereto.

20 I am aware that supports of various types have been used to protect the foot of the wearer in climbing ladders, in shoveling, and to protect the foot against heat and moisture.

I am also aware that arch supports are well 25 known and worn either inside or outside the shoe, the latter being exemplified in Patent No. 1,728,219, to J. A. Smith.

I am also familiar with the Thomas bar, as used in foot orthopedics, for the support of 30 metatarsal bones.

None of these known devices attains the result accomplished by my novel foot support, whereby the user is enabled to walk in a substantially normal manner and with normal 35 comfort, while substantially limiting or entirely preventing flexure of the joints at the metatarsal head or anterior thereto.

The following is a description of my device, as shown in the drawing, and the essential features 40 of which are summarized in the claims:

In the drawing, Fig. 1 is a general perspective view of my support; Fig. 2 is an elevation showing the support in position beneath a shoe, while Fig. 3 is a plan view, taken from below, showing the support in position on a shoe. In Figs. 2 and 3 the bones of a normal foot are shown in dotted lines, for more clearly indicating the use 45 of my support.

The foot support 10 may be made of any suitable material, but preferably of wood. The support is indicated as having a substantially plane lower surface 11, and an upper surface, divided into a heel portion 12, a shoulder 13, adapted to rest against the breast of the heel of a shoe and 50 to contact the arch of the sole, and a front por-

tion 14, conforming to the normal contour of the shoe sole and ending at 15 under the ball of the foot, and beneath or slightly behind the heads of the metatarsal bones. Both the top and bottom edges of the front end of the support may 60 be slightly curved, or both may be straight, but I prefer to have the upper edge curved, as at 15, to accommodate it to the natural location of the bones, and the lower edge 17 straight, as an aid in walking. The edges may be rounded off, if 65 desired.

The support may be fastened to the shoe by any suitable fastening means, the straps 16, being shown for illustrative purposes only.

In Figs. 2 and 3 the foot support 10 is shown 70 in proper place beneath a shoe 21, and the dotted lines show the bones of a foot in normal position within the shoe. The phalanges are indicated at 18, the metatarsals at 19, and the metatarsal heads at 20. It will be noted that 75 the support ends at the point 15 adjacent the metatarsophalangeal joint, and preferably slightly to the rear thereof in a position to support the metatarsal heads 20. The foot and shoe are raised from the ground but are otherwise in 80 substantially normal position. The height of the support at 15 raises the foot substantially above the ground. The weight of the body is distributed evenly over the heel, arch and a portion 85 of the ball of the foot.

In walking, the heel and arch of the user are supported in normal position by the parts 12, 13 and 14 of the support, and the weight of the body is pivoted about the point 17. The foot may be held sufficiently off the ground to permit a normal flexure of the knee in walking and the corresponding downward movement of the front portion of the foot with the transmission of little or no movement to the phalanges 18 or the metatarsophalangeal joint 18—19. I have 90 found that the thickness of the support at the point 15—17 may be made approximately one inch to give good results, but this dimension may be varied without departing from the spirit and purpose of my invention.

I have found an advantage in making the support of wood as it allows the user easily to change the shape to suit his individual case.

I claim:

1. A foot support extending from the rear of the foot to a point beneath the ball of the foot, and ending adjacent the metatarsophalangeal joint of a user's foot, and said support maintaining the foot substantially parallel to its nor- 110

mal position and approximately one inch above the normal position at the said point.

2. A substantially rigid foot support extending from the rear of the foot to a point beneath the ball of the foot, and ending adjacent the metatarsophalangeal joint of a user's foot, and said support maintaining the foot substantially parallel to its normal position and sufficiently above the surface walked upon to permit substantially normal flexure of the knee of the user when walking without the toes of said user being bent by contact with said surface.

3. A foot support extending from the rear of the foot to a point beneath the ball of the foot and ending at the metatarsophalangeal joint of a user's foot, the support at the latter point maintaining the foot sufficiently above the surface walked upon to prevent flexure of said joint when a substantially normal step is taken.

4. A foot support extending beneath the heel, arch and a portion of the ball of the foot, said support ending at a point beneath the ball of the foot adjacent the metatarsophalangeal joint of a user's foot, and said support at the latter point maintaining the foot sufficiently above the surface walked upon to prevent appreciable flexure of said joint when a normal step is taken.

5. A foot support extending beneath the heel, arch and a portion of the ball of the foot, said support ending at a point beneath the anterior heads of the metatarsal bones of a user's foot and said support maintaining the foot parallel to and sufficiently above its normal walking position to prevent contact of the user's toes with the ground when a substantially normal step is taken.

6. A foot support adapted to be secured to the bottom of a shoe, the upper surface of said support having a portion beneath the heel, a shoulder portion adapted to contact the arch of the shoe and a portion following the curve of the sole and ending beneath the metatarsophalangeal joint of a user's foot, the support at the latter point having upper and lower surfaces adapted to support the ball of the foot across substantially the entire width of the foot and at a height sufficiently above the surface walked upon to prevent appreciable flexure of said joint.

7. A foot support adapted to be secured to the bottom of a shoe, said support having a substantially plane lower surface and the upper surface having a portion beneath the heel, a shoulder portion adapted to contact the arch of the shoe, and a portion following the curve of the sole and ending at a point beneath the metatarsophalangeal joint of a user's foot, the support at the latter point being substantially one inch thick.

8. A foot support comprising a substantially rigid integral member having its upper surface conforming to the heel and sole of a human foot, said member ending beneath the ball of the foot, the front end of said member extending transversely of the foot and having its upper edge curved convexly forward and having its lower edge straight, and said member having lower surfaces beneath the heel and ball of the foot, said lower surfaces lying in a common plane approximately one inch below the upper front edge of said member.
